UNITED STATES PATENT OFFICE.

PETER F. GALLAGHER, OF BALTIMORE, MARYLAND, ASSIGNOR, BY DIRECT AND MESNE ASSIGNMENTS, TO FLANNERY BOLT COMPANY, OF PITTSBURGH, PENNSYLVANIA, A CORPORATION OF PENNSYLVANIA.

FLEXIBLE STAYBOLT.

1,323,040.

Specification of Letters Patent.

Patented Nov. 25, 1919.

Application filed August 9, 1915. Serial No. 44,638.

To all whom it may concern:

Be it known that I, PETER F. GALLAGHER, a citizen of the United States, residing in the city of Baltimore and State of Maryland, 5 have invented new and useful Improvements in Flexible Staybolts, of which the following is a specification.

My invention relates to flexible stay bolts for connecting the outside and fire box 10 sheets of a boiler, and particularly to an improved construction of seat flange or thimble in which the outer end or head of the bolt is pivotally mounted, and mode of connecting said flange or thimble to the 15 outside sheet.

The object of the invention is to provide a construction of flange or thimble and wall or outside sheet, whereby the flange or thimble may be firmly secured within a 20 receiving opening in the sheet against any possibility of becoming loosened or disconnected, giving all of the advantages of an integral connection of the thimble or flange with the sheet at less cost while enabling 25 new flanges or thimbles to be applied in case of damage or injury to those in use.

A further object of the invention is to provide a flange or thimble which overcomes the disadvantages of threaded thimbles or 30 sleeves in strengthening instead of weakening the outside sheet about the bolt hole, and which may be set at any angle to bring the bolt holes in the inside and outside sheets into alinement, thus disposing the bolt so 35 that the pulls resulting from stresses and strains will fall upon the bolt and sheet connections in a straight line.

The invention consists of the features of construction, combination and arrangement 40 of parts, hereinafter fully described and claimed; reference being had to the accompanying drawing, in which: Figure 1 is a sectional view through portions of a boiler illustrating the application of my invention.

45 Figs. 2 and 3 are sectional views illustrating a certain capability of the invention.

Referring to the drawing, 1 designates the inside or fire box sheet, 2 the outside sheet, and 3 the stay bolt. As shown in the present 50 instance, the sheet 1 is provided with a threaded opening 4 in which the threaded inner end 5 of the bolt is fitted and secured, such end of the bolt being riveted or headed, as shown at 6. This end of the bolt may,

however, be secured to the inside or fire sheet 55 in any other suitable manner.

The outer end of the bolt 3 is provided with a head 7 having a partly spherical convex surface 8. This surface 8 pivotally engages a concaved seat surface 9 within the 60 outer end of a seat flange, sleeve or thimble 10, so as to permit the bolt to have proper pivotal movements to accommodate itself to expansion and contraction of the boiler sheets. The outer end of the said seat flange 65 or thimble is of cylindrical form and is externally threaded, as shown at 11, for engagement with the threaded flange of the usual cap or cover 12, between which and the outer edge of the flange or thimble may be 70 interposed an elastic gasket 13.

In accordance with my invention, the wall or sheet 2 is provided with a receiving opening 14 which flares in an outward direction, being of smallest diameter at its inner end 75 and of maximum diameter at its outer end, and having its wall inclining at substantially an oblique angle in an outward direction. This opening receives the inner end 15 of the thimble 10 which is bell-mouthed in 80 shape or flared to a corresponding degree in the opposite direction. The inner end of the thimble is arranged to lie flush with the inner surface of the sheet 2, and by reason of the relative outward divergence of the 85 wall of the opening 14 and inner end of the thimble a flaring space 16 is provided within the inner end of the thimble to permit the bolt to have free universal pivotal motion, while a V-shaped annular channel or recess 90 is provided between the inner end of the thimble and the wall of the opening 14 to receive a welding filling 15' of a suitable welding metal or composition.

In preparing the outside sheet for the reception of the seat thimbles, the openings 14 are first formed and the inner ends of the thimbles fitted in position, the welding composition or filler introduced and the weld made by the use of an oxy-acetylene welding 95 apparatus, thus fusing the metals together so that the union between the sheet and thimble is of a homogeneous character. By this means all of the advantages of a flange or thimble integral with the sheet may be 100 obtained, namely, greater strength and rigidity and freedom from leakage, loosening or disconnection of the parts at the joint,

while at the same time the expense of construction is reduced to a material degree. By reason of the shape of the opposing surfaces of the opening 14 and thimble any possible tendency to displacement of the thimble is resisted by a union of wedge formation, whereby maximum resistance to deflection, fracture or displacement is secured.

In constructing a locomotive boiler it is not absolutely necessary to stay the outside wrapper sheet, since, owing to its contour, this sheet has sufficient strength in itself, but it is necessary to stay the inside or fire box sheet, and to this end flexible stay bolts are commonly employed which are extended between and connected with the two sheets, and which, owing to the different curvatures of the inside and outside sheets, are arranged in radial series struck from different centers. Owing to this arrangement, some of the bolts extend at an angle, making it impossible, with the use of threaded sleeves or thimbles, to secure more than one complete thread for the connection of the thimble in the thickest part of the metal of the outside sheet, which is ordinarily not more than one-half inch. The objection to this is that after the boiler is in service leakage starts at the threaded opening, and as, with the use of a threaded sleeve, there is but a single thread to depend upon, it is usually the case that the sleeve has to be removed, the hole retapped and another threaded sleeve applied, which only overcomes the trouble temporarily. These and other objections render the use of thread sleeves annoying and a source of considerable trouble and expense in requiring frequent repairs to be made.

Owing to differences in expansion and contraction, it frequently occurs that the inside and outside sheets become relatively distorted, sufficiently in many cases to throw the sets of bolt holes out of alinement and cause angular strain upon the stay bolts. In renewing a fire box sheet, it also frequently happens that the substitute fire box sheet is not always the exact duplicate of the original, and hence when this new fire box sheet is set in position for connection the sets of coöperating stay bolts are not disposed in proper alinement. In the use of threaded sleeves or thimbles, it is hard to overcome this difficulty, and it can not be overcome without some of the bolts being set at an angle, with the result that the pulling strains are transmitted at an angle to the bolt instead of in a straight radial line. By the use of my invention these several and various objections are overcome, as the thimble or sleeve can be set with its long axis approximately coincident with the long axis of the bolt. Again the welding connection of the thimble or sleeve with the sheet makes a connection absolutely proof against leak-

age, and also makes the sheets stronger and more durable about the bolt hole, and the substitution, except in case of actual damage, of new sleeves for the original sleeves to prevent leakage is entirely avoided and overcome. Furthermore, as indicated clearly in Figs. 2 and 3, in the event that the coating bolt holes in the inside and outside sheets should be found to be out of alinement upon applying the bolt, this may be easily corrected by reheating the sleeve, which is made of ordinary boiler plate or steel, applying a dummy bolt A and dummy cap B, and then by means of a flatter and sledge bending or setting the sleeve at an angle in one direction or the other to bring the bolt holes in alinement, as will be readily understood.

Other advantages of my improved thimble or sleeve is, that it allows a greater degree of flexibility than other forms of sleeves or thimbles, that it is stronger and more durable than any other sleeve or thimble because it may be made heavier than a threaded thimble, and after being welded into the sheet gives both greater strength and durability to itself as well as to the sheet. Moreover, the thimble may be bent or set to lie at any acute angle, to dispose the bolt properly for a straight pulling strain along its fixed radial line, without any tendency to cause leakage, as is the case in the use of threaded sleeves.

Further, the application of the thimble by the method is permanent, it not being necessary to renew this thimble unless the outside sheet is removed.

I claim:—

1. In a stay bolt connection for boilers, the combination of an outer sheet having an opening, a thimble within the opening and of a shape and size whereby it may be adjusted at different angles to aline with the bolt opening in the other sheet, the said thimble being welded to the said outer sheet.

2. In a stay bolt connection for boilers, the combination of a boiler sheet formed with an opening flared in an outward direction, a thimble having a reversely flared inner end fitted within said opening, a substantially V-shaped recess being thereby formed between the wall of the opening and flared portion of the thimble, a welding filler of wedge formation in cross section occupying said recess and binding the thimble in a substantially homogeneous manner to the boiler sheet, and a stay bolt having pivotal engagement with said thimble.

3. The combination with a boiler sheet and a thimble forming a bearing sleeve for a bolt, said boiler sheet provided with an opening having a part appreciably greater in diameter than the diameter of a portion of the bearing sleeve which enters said opening, whereby an annular space is formed to receive welding material to weld the sleeve

to the boiler sheet, and which permits of the adjustment of the sleeve to aline with the stay bolt hole in the inner sheet of the boiler.

4. The combination of a boiler sheet having a stay bolt opening therein, a bearing sleeve entering said opening, there being a space between the sleeve and the wall of the opening, and welding material within said space and fused to the sleeve and wall of

the opening, the said sleeve having a bearing therein for the head of a stay bolt.

In testimony whereof I affix my signature in presence of two witnesses.
